APPARATUS FOR MAINTAINING CONSTANT HEAT VALUE.

1,417,635.

Specification of Letters Patent.

Patented May 30, 1922.

Application filed March 11, 1918. Serial No. 221,747.

To all whom it may concern:

Be it known that I, HARRY F. SMITH, a citizen of the United States, residing at Lexington, in the county of Richland and State of Ohio, have invented certain new and useful Improvements in Apparatus for Maintaining Constant Heat Value, of which the following is a full, clear, and exact description.

10 This invention relates to gas regulation and more particularly to the regulation of gas for maintaining a constant heat value therein.

When gas is used for either fuel or power purposes, it is very difficult to secure maximum efficiency and constant operating conditions because of fluctuations in the heat value of the gas. These fluctuations of heat value may arise from a number of different causes. Where natural gas is used, for instance, such fluctuations are always attendant upon variations in the pressure of the gas. Also, where an artificial gas, such as producer gas is used, such fluctuations will 25 occur because of variations in the pressure of the gas, and in addition because of variations within the generating chamber itself which give rise to variations in the character of gas generated. Obviously it is desirable

30 in many cases to secure constant temperature conditions. If the gas being used is of uniform character so far as the chemical composition thereof is concerned, in other words if the heat value of that gas per unit volume remains constant, it is quite easy to secure uniform temperature conditions by simply insuring a uniform flow of gas to the combustion zone. If, however, the heat value of the gas is a variable quantity, it is 35 obvious that maintaining a constant volume of flow of gas to the point of combustion will not insure a uniform temperature, inasmuch as the heat of combustion will vary with variations in the heat value of the gas.

40 If a gas is supplied in which the heat value per unit volume is maintained constant, the problem of maintaining uniform temperature conditions is obviously solved.

One object of the present invention is to 50 provide a method for insuring a constant heat value in natural gas, producer gas or any other form of gaseous fuel, and means for carrying that method into effect, which means is automatic in its operation, is inexpensive and substantial in structure, is

easily maintained in repair and is yet thoroughly practicable in its application.

In carrying this invention into effect I provide a valve controlled leak in the gas main through which atmospheric air, or, if preferred, other diluting fluid, is allowed to pass to mingle with the gas in the main with a consequent dilution of that gas, the degree of dilution depending upon the character of the gas in the main and the heat value which it is desired to maintain therein. Controlling this leak valve is suitable mechanism adapted to automatically vary the flow of air therethrough, to accord with variations in the heat value of the gas itself. 70

In the accompanying drawing I have illustrated several forms of mechanism for carrying out my invention, each form being adapted for so controlling the admission of air, or other diluting fluid, to the gas main that a constant heat value is maintained in the gas. In the drawing, in which like characters of reference designate like parts throughout the several views thereof, 75

Fig. 1 illustrates a form of apparatus for 80 insuring constant heat value in the gas having electrically operated means for controlling the leak valve;

Fig. 2 discloses another embodiment of the apparatus having a modified form of electrically operated valve actuating mechanism; 85

Fig. 3 discloses still another embodiment of the invention in which the leak valve is controlled by pressure operated means. 90

Referring to Fig. 1 of the drawing, 1 is a gas main. This gas main may lead from any suitable source of supply, as, for instance, a gas producer or a source of supply of natural gas. This invention is by no 95 means limited in its applicability to the treatment of some particular kind of gaseous fuel, but is capable of use with any form of gaseous fuel in which it is desired to maintain a constant heat value. As illustrated the gas in the main 1 is drawn therethrough by means of the pump 2, which is adapted during operation to draw gas from the source of supply through the main 1 and to force that gas after it leaves the pump 100 through the main 3, which leads to any desired place of use. This invention has been worked out especially for use in connection with a suction gas producer, the pump 2, as illustrated, being just such a pump as is 110

ordinarily used for causing suction through such a producer and for forcing the gas from the producer through the gas main to the place of use. The gas passing through the main 1 is of variable heat value, the recording calorimeter 4 being applied to the main 1 in order to show the actual heat value thereof. The object of the present invention is to so treat the gas as it passes through the 10 main as to insure a constant heat value therein when delivered to its place of use.

Located in the main 1 is a port 5, the effective opening through which may be varied by means of the valve 6. This port 15 5 is located on the suction side of the pump 2 and is so controlled by the valve 6 that there will under all ordinary conditions be a flow of diluting fluid therethrough into the main, the amount of such flow being dependent upon the effective opening through 20 the port. In ordinary practice the port 5 is adapted to admit atmospheric air into the main, but it is obvious that any form of diluting fluid may be substituted therefor, 25 such for instance as exhaust gases.

The stem 7 of the valve 6 is operatively connected to the diaphragm 8 of the pressure operated diaphragm regulator 9. Surrounding the stem 7 and cooperating with the 30 diaphragm 8 is a spring 10 normally tending to urge the valve 6 away from its seat to increase the effective opening through the port 5. Opening into the diaphragm regulator is a pipe 11 adapted to supply a pressure fluid thereto in such wise as to act upon the diaphragm 8 and exert a force thereon tending to 35 counteract the action of the spring 10. The normal tendency of the spring 10 to urge the valve 6 from the seat is counteracted more or less completely by the fluid pressure introduced through the pipe 11, so that the degree of opening of the valve 6 will depend upon the relative forces exerted upon the 40 opposite sides of the diaphragm 8 by the spring and the pressure fluid. The pipe 11 has opening thereto a pipe 12 which is connected to any suitable source of fluid under 45 pressure, flow of such fluid under pressure, through the pipes 12 and 11, into the diaphragm regulator 9 being controlled by the valve 13. Leading off from the pipe 11 is an exhaust pipe 14, having a controlling valve 15 located therein. The exhaust pipe is adapted to lead off from the diaphragm 50 regulator 9 through the pipe 11 the fluid under pressure contained therein to thus dissipate the pressure upon the diaphragm 8 tending to counteract the opening tendency of the spring 10. The valves 13 and 15 consist of cylindrical metallic members, located 55 in enlargements in the pipes 12-14 controlled thereby. Each of these valves is normally held against its respective seat 13'-15' by the downward action of gravity. The arrangement of the valves in the pipes 12-14

is such that they normally remain seated, unless positively moved upwardly from their seats, thus preventing flow into the diaphragm regulator through the pipe 12, or exhaust therefrom through the pipe 14.

Leading off from the main 3 is a pipe 17 adapted to permit of flow therethrough of a part of the gas passing through the main 3. Inserted in the pipe 17 is a pressure regulator 18 adapted to maintain a constant pressure 70 in the pipe therebeyond regardless of fluctuations of pressure in the main 3. The type of pressure regulator illustrated is purely conventional in structure and any other desired type of regulator may be used, the 80 precise form of regulator used being immaterial inasmuch as the structure thereof forms no part of the present invention. Inserted in the pipe 17 beyond the pressure regulator 18 is a diaphragm 19 having a constant orifice 20 therein. Inasmuch as the pressure regulator 18 insures a constant pressure at the orifice 19 and such orifice is itself constant, the flow of gas therethrough 85 will also be at all times a constant quantity. 90

Attached to the free end of the pipe 17 is a gas burner 21 of any desired form, which burner extends inside the chamber 22. The side and bottom walls of this chamber are closed except for certain air inlet ports 23 95 in the bottom thereof for supplying sufficient quantity of air to insure complete combustion of all gas passing through the burner. The upper end of the chamber 22 is left open so that the heated products of 100 combustion resulting from burning the gas passing through the pipe 17 and burner 21 will pass upwardly through the chamber. Located in the chamber 22 in such wise as to be acted upon by the heated gases passing 105 therethrough is a thermostatic strip 24 attached to a bracket 25 which is insulated from the wall of the chamber 22 by means of any desired insulating material 26. Passing through the wall of the chamber 22 are 110 two contact elements 27 which are insulated therefrom by means of insulating plugs 28. The form of insulation shown in connection with the thermostatic strip 24 and the contact elements 27 is purely conventional, and 115 any other desired means of insulating these elements may be employed. The contact elements 27 extend into the chamber 22 and their inner ends are located adjacent the free end of the thermostatic strip 24 and 120 upon opposite sides thereof. Any increases or decreases in the amount of heat generated at the burner 21 will cause a deformation of the thermostatic strip toward one contact element or the other, the sensitiveness of the 125 thermostatic strip and the relative position of the two contact elements being such that in actual practice a very slight deformation of the strip in either direction will cause it to contact with one of these elements. 130

Surrounding each of the enlargements containing the valves 13—15 is a solenoid 29, the arrangement being such that each of the valves constitutes in effect a core for its surrounding solenoid, so that energizing either solenoid will cause axial movement of the valve co-operating therewith to lift that valve from its seat and thus permit flow through the pipe controlled thereby. Leading off from the thermostatic strip 24 is a conductor 30, connected with one terminal of each of the solenoids 29. Leading off from one of the contact elements 27 is a conductor 31 and leading off from the other contact element 27 is a conductor 32. The conductor 31 is connected to the other terminal of one of the solenoids 29, while the conductor 32 is connected to the other terminal of the other solenoid 29. Located in each of the conductors 31 and 32 is a battery 33. From the above structure it is obvious that when the thermostatic strip 24 is so deformed as to cause it to contact with either of the contact elements 27, there will be a flow of current from the battery 33, co-operating with that particular contact element 27, through the corresponding solenoid 29 to energize that solenoid and cause movement of the valve co-operating therewith with an ensuing building up or dissipation of the pressure in the diaphragm regulator 9.

Inasmuch as the pressure regulator 18 and the constant orifice 20 insure the delivery of a constant quantity of gas to the burner 21, it is obvious that any variations in the amount of heat generated at such burner are due to variations in the heat value of the gas. Any variations in the quantity of heat thus generated at the burner 21 will effect the thermostatic strip 24 to cause deformation thereof toward one or the other of the contact elements 27. If variation in the amount of heat generated at the burner 21 occurs with consequent deformation of the thermostatic strip 24, there will be a resulting actuation of one of the valves 13—15 with a corresponding deformation of the diaphragm 8, to thus increase or decrease the effective opening through the port 5 to increase or decrease the quantity of air or other diluting fluid flowing through such port into the main 1. If the heat value of the gas being burned at 21 increases, the thermostatic strip will be deflected to contact with that one of the contact elements 27 controlling flow of the current through the solenoid controlling the valve 15 to thus open that valve with a consequent exhausting of the fluid pressure in the diaphragm 9 to increase the effective opening through the port 5 and permit the admission of a greater quantity of diluting fluid to cut down the heat value of the gas in the main. If the heat generated at the burner 21 decreases, the thermostatic strip 24 will contact with

the other element 27 to close the circuit through the solenoid controlling the valve 13 to open that valve and permit a greater quantity of pressure fluid to flow therethrough to bring about a decrease in the effective opening through the port 5 with a corresponding decrease in the amount of diluting fluid passing therethrough, to thus cause a relative increase in the heat value of the gas flowing through the main 3. The valve 6 is adjustably mounted on its stem and is so set that a definite amount of diluting fluid is passing through the port 5 when the gas in the main 3 is of the desired heat value. By thus having the port 6 normally open a predetermined amount, it is possible to permit a decrease in the effective opening therethrough, as would be desirable when the heat value of the gas falls below normal, as well as an increase in the effective opening therethrough, as would be desirable where the heat value of the gas rises above normal.

In Fig. 2 is illustrated another form of apparatus which comprises modified means for controlling the valve 6. In this modification the gas mains are the same as illustrated in Fig. 1 and have a valve controlled leak port, similar to that described above, co-operating with the main 1. Further the calorimeter 22 and the means for supplying a constant quantity of gas to the burner thereof are the same as the corresponding mechanism illustrated and described in Fig. 1. No further description is, therefore, given of these features of the apparatus illustrated in Fig. 2, but they have been given the same numerals as the corresponding parts in Fig. 1 and their structure, operation and function will be apparent upon reference to the description matter above.

Leading into the diaphragm regulator 9 is a supply pipe 11 connected to a source of fluid under pressure by means of the pipe 12. Located in the pipe 12 and adapted to control flow therethrough is a valve 34 having an actuating handle 35 connected thereto. As shown this valve 34 is a conventional turning plug but any other suitable valve may be substituted therefor. Leading off from the pipe 11 intermediate the valve 34 and the diaphragm regulator 9 is an exhaust pipe 36 having a controlling valve 37 located therein. This valve is shown as of a conventional reciprocating type; but any other suitable form of valve may be substituted therefor, it being merely necessary that such valve be capable of affording a nice control of flow through the pipe 36. If the effective opening through the valve 37 is kept constant, pressure on the diaphragm 8 may be varied as desired by increasing or decreasing the amount of pressure fluid flowing through the valve 34. In order to control the effective opening through the port 5 it is merely necessary, therefore, to so control the

valve 34 as to admit a relatively greater or less quantity of pressure fluid therethrough.

Located upon opposite sides of the actuating handle 35 are two solenoids 38. Each 5 of these solenoids has therein a core 39, one end of which is connected to the actuating handle 35 by means of a link 40. Each of the links 40 is pivotally connected to the actuating handle 35 and to its co-operating core 39, these parts being so arranged that 10 axial movement of either core will cause a corresponding movement of the actuating handle 35 to vary the effective opening through the valve 34. The solenoids 38 are 15 connected to the thermostatic strip 24 and contact elements 27, which are associated with the calorimeter 22, as described in connection with Fig. 1.

The operation of this modification is 20 thought clear. If because of any variation in the heat value of the gas supplied to the burner 21 a greater or less quantity of heat is generated in the calorimeter, the thermostatic strip 24 will be deformed to cause contact thereof with one of the contact elements 25 27 to thus close the circuit through one of the solenoids 38 to energize that solenoid.

And energizing either of the solenoids will cause an axial movement of the core 39 co- 30 operating therewith to bring about a corresponding movement of the valve 34 which, by varying the pressure in the diaphragm regulator 9, will vary the effective opening through the leak port 5. It is obvious that 35 the solenoids are so connected to the batteries 33 that one solenoid when energized will tend to increase the effective opening of the valve 34 while the other solenoid when energized will tend to decrease the effective 40 opening through this valve.

In Fig. 3 I have shown still another modified form of my invention in which pressure operated means is used for varying the effective opening through the leak port 5. In 45 the modification disclosed in this figure the electrically operated actuating means is dispensed with and in place thereof a closed vessel 41 is located within the calorimeter 22 in such wise as to be subjected to the heat of 50 combustion at the burner 21. The vessel 41 may contain a gas or vapor therein, or, if desired, a fluid which will readily vaporize at the temperature existent in the calorimeter. Any variation in the amount of heat 55 to which the vessel 41 is subjected, will, therefore, result in an expansion of the gas vapor therein, or, where a liquid is used, in the generation of an increased quantity of vapor, which will cause an increase of pressure 60 within the vessel. This vessel has leading off therefrom a pipe 42, the free end of which opens into a bellows like chamber 43 adapted to expand or contract, i. e., to increase or decrease in length, according as the pressure 65 therein increases or decreases. And any

such increase or decrease of pressure in the bellows like member 43 will result from corresponding variations of pressure in the vessel 41 due to the variations in the amount of heat generated at the burner 21.

Pivotedly attached to the free end of the member 43 by means of a link 44 is a lever 45 fulcrumed at 46 to some fixed part of the apparatus. Pivotedly mounted adjacent the lever 45 is a bell crank lever 47, one arm 75 of which is pivotally connected by means of a link 48 to the adjacent end of the lever 45, the other arm being operatively connected to the stem of the valve 6 by means of a link 49. In this form of apparatus the dia- 80 phragm regulator 9 for controlling the valve 6 is dispensed with, as are also the various parts of the apparatus necessary for controlling the supply of pressure fluid to that dia- phragm regulator in order to bring about 85 the desired actuation of the valve 6. In place of this diaphragm regulator and co- operating mechanism, I have substituted the positive lever-controlling mechanism de- 90 scribed above.

If the heat value of the gas flowing through the main 3 increases it is evident that the heat generated at the burner 21 will also increase. This increase in the amount of heat generated in the calorimeter 22 will cause an increase of pressure in the vessel 41, which, acting through the pipe 42, will also cause an increase of pressure in the bellows like member 43, with a consequent elongation of that member. Such elongation of the member 43 will cause a rotation of the lever 45 about its fulcrum 46 to rock the bell crank lever 47, with a consequent actuation of the valve 6 to increase the effective opening through the port 5. And ob- 100 95 105 110 115 120 125 130

viously any decrease in the amount of heat generated at the burner 21 will cause a rocking of the bell crank lever 47, with a corresponding actuation of the valve 6 to decrease the effective opening through the port 5. In order to secure a constant heat value in the gas passing through the main 3, it is merely necessary to set the valve 6 so that a certain, definite amount of diluting fluid will pass through the port 5 under normal conditions. To permit of such initial setting of the valve 6 I have shown that valve, in each form of apparatus illustrated, as adjustably mounted on its stem so that it may be readily moved axially thereof. After being set, if any variation in the heat value of the gas occurs the controlling apparatus will automatically actuate the valve to admit a greater or less quantity of diluting fluid to thus return the heat value to normal. Each of the forms of apparatus illustrated is thus entirely automatic in action so that a constant heat value will be insured in the delivered gas regardless of fluctuations there- in at the time of leaving its source.

From the above description it is evident that I have invented a very simple and practical method of insuring a substantially constant heat value in a gaseous or vaporous fuel, and effective apparatus for carrying that method into operation. While I have illustrated several such forms of apparatus my invention is by no means limited to the precise structural details herein disclosed, inasmuch as numerous modifications might be made without in any way departing from the spirit of that invention. For a definition of the scope of my invention, therefore, reference should be had to the appended claims.

15. What I claim as new is:

1. In a device for maintaining a substantially constant heat value in a fluid conveying means; the combination of a valve for admitting a diluent to the fluid within the main; pressure operated means for controlling said valve; electrically operated means for controlling the pressure operating said pressure operated means; means for withdrawing from the main a constant quantity 25 of the diluted fluid; means for burning such withdrawn fluid; and means responsive to variations in the heat generated by the burning fluid adapted to actuate the electrically operated means to vary the amount of diluent admitted to accord with variations in the heat generated by the burning fluid.

2. In a device for maintaining a constant heat value in a gas, the combination of a gas conveying main; a pump for forcing the gas through the main; a valve controlled leak port connecting the inside of the main, in advance of the pump, with the atmosphere; means beyond the pump through which a constant quantity of the gas passes out from the main; means for burning such constant quantity of gas so withdrawn; and heat responsive means associated with said gas burning means and adapted to vary the effective opening through the leak port to accord with variations in the heat generated by the burning gas.

45. 3. In a device for maintaining a constant heat value in a fluid, the combination of a conveying main; a pump for forcing the fluid through the main; a valve in advance of the pump for controlling a port in the

main through which a diluent may be admitted to the fluid within the main; pressure operated means for actuating said valve; electrically operated means for varying the pressure operating the said actuating means; means beyond the pump through which a constant quantity of the diluted fluid will pass out of the main; means in which such fluid may be burned; and means, responsive to any fluctuations generated by the burned fluid, adapted to cause functioning of the electrically operated means to vary the opening of said valve to accord with such fluctuations.

4. In a device for maintaining a constant heat value in a fluid, the combination of a conveying main; a pump for forcing fluid through the main; a valve controlling a port in the main, through which a diluent may be admitted into the main; pressure responsive means for actuating said valve; means for controlling the pressure upon such actuating means; a fluid burner; means for delivering a constant quantity of fluid to the burner; and heat responsive means associated with said burner adapted to actuate the pressure controlling means to accord with variations in the heat generated at the burner.

5. In a device for maintaining a constant heat value in a fluid; the combination of a conveying main; a pump for forcing the fluid through the main; a valve controlling a port in the main, through which a diluent may be admitted into the main; pressure responsive means for actuating said valve; electrically operated valve mechanism for controlling the pressure upon such actuating means; a fluid burner; means for continuously delivering a constant quantity of fluid to the burner; thermostatic means associated with such burner and responsive to variations in the heat generated by the fluid burned thereat; said thermostatic means constituting a control for the electrically operated valve mechanism whereby said mechanism is caused to vary the functioning of the pressure responsive means to accord with variations in the heat generated at the burner.

100. In testimony whereof I affix my signature.
HARRY F. SMITH.
